ROTARY TEETER

Filed Dec. 1, 1927

Inventor
EWING H. TAYLOR

Ch. F. Andersen

Attorney

UNITED STATES PATENT OFFICE

EWING HORACE TAYLOR, OF BEAUMONT, TEXAS

ROTARY TEETER

Application filed December 1, 1927. Serial No. 237,089.

This invention relates to rotary teeters and is a continuation in part of my application Serial No. 141,805, filed October 15th, 1926.

5 An important object of the invention is to provide a novel form of teeter including a trackway having a series of undulations providing alternate high and low portions and adapted to effect a teetering action of the teeter board, the latter being rotatably supported in such a manner that the teetering action effects rotation thereof about a vertical axis.

10 A further object is to provide a device 15 of the above mentioned character wherein the teeter board is provided with novel roller means adapted to contact with the trackway in such a manner as to reduce friction between the rollers and trackway to permit 20 the device to be operated with little effort.

15 A further object is to provide a trackway extending vertically from a preferably integral base and constituting therewith a 25 lubricant container into which a portion of each roller is adapted to dip to be provided with lubricant as the teeter board rotates.

20 A further object is to provide a novel 30 form of roller having a central peripheral groove to receive the trackway and inner and outer guide flanges, the inner flange being of material depth to permit it to dip into the lubricant container to be supplied with lubricant therefrom as the roller passes 35 over each low point of the trackway.

25 A further object is to provide a novel 30 casing for the operating elements of the device to prevent injury therefrom while the device is in operation.

40 Other objects and advantages of the invention will become apparent during the course of the following description.

45 In the drawings I have shown one embodiment of the invention. In this showing,

Figure 1 is a central vertical longitudinal sectional view, parts being shown in elevation;

50 Figure 2 is a section on line 2-2 of Figure 1, parts being shown in elevation,

Figure 3 is a plan view of the trackway;

Figure 4 is a detail sectional view of one of the rollers and supporting means therefor, and,

Figure 5 is a detail view of the protecting casing.

Referring to the drawings the numeral 10 designates a preferably tubular pedestal mounted upon a base 11 which may be secured on any supporting surface in any desired manner. A trackway indicated as a whole by the numeral 12 is arranged at the upper end of the pedestal. As shown, the member 12 is provided with a base 13 and a depending flange 14, which may be threaded on the upper end of the pedestal 10, as shown in Figure 1. The trackway proper comprises a plurality of undulations providing alternate high and low points 15 and 16, as shown in Figures 1 and 3. The low points of the trackway are preferably arranged a substantial distance above the base portion 13 whereby the trackway cooperates with the latter element to provide a container for a body of lubricant 17.

75 The member 12 is provided axially thereof with a bearing 18 rotatably receiving a shaft 19 which may be formed integral with a head 20. This head is adapted to receive a transverse shaft 21 which passes through the depending arms 22 of a substantially U-shaped support 23, the latter element being bolted or otherwise secured as at 24 to a teeter board 25. The teeter board may be provided adjacent opposite ends with hand holds 26, the purpose of which is apparent.

80 On opposite sides of the trackway the teeter board is provided with pairs of spaced depending bearings 27, and a shaft 28 is mounted in each pair of bearings. These shafts may be secured against longitudinal movement with respect to their corresponding supporting bearings by set screws 29, and the shafts referred to also may be provided with cotter pins 30. A roller 31 is mounted on each shaft 28, and it will be apparent that the thickness of each roller is materially less than the distance between 85

the corresponding bearings 27. Each roller is adapted to rotate upon its shaft 28 and to partake of sliding movement thereon. Each roller is provided with a central peripheral groove 32 which is adapted to roll upon the undulations of the trackway. This groove forms inner and outer annular flanges 33 and 34 respectively, the flange 33 being of substantially greater diameter than the groove 32, for a purpose to be described.

Means is provided for protecting persons using the device from being injured by the operating parts thereof. Cleats 35 may be secured against the sides of the teeter board centrally thereof, or the board may be made wider at these points. A casing 36 is arranged beneath the central portion of the teeter board and is provided on opposite sides with upward projections 37 having openings 38 therein to receive nails or screws by means of which the casing may be secured against the cleats 35. The casing 36 is sufficiently wide to clear the sides of the operating elements of the device as shown in Figure 2, and is elongated longitudinally of the teeter board to permit the latter to oscillate about the axis of the shaft 21 without the casing striking the pedestal 10 or other parts of the apparatus.

The operation of the device will be apparent from the foregoing description. Vertical oscillation of the teeter board causes the rollers 30 and 31 to travel from the low to the high points of the trackway undulations, and vice versa, thus causing the board to rotate about the axis of the shaft 19. Thus the board will be caused to rotate about a vertical axis and oscillate about a horizontal axis. The use of grooved rollers which are adapted to partake of radial sliding movement with respect to the vertical axis of rotation permits the rollers to alter their positions according to the distances from the axis of the shaft 21 to the points of contact between the rollers and the trackway, and the friction between these elements is materially reduced, thus permitting the device to be operated with very little effort. As previously stated, the trackway constitutes a lubricant container, and a body of lubricant may be maintained therein to the level of the low points of the undulations. Thus each time one of the rollers passes over the low points of the trackway, the inner flange 33 thereof will pick up lubricant and supply it to the contacting surfaces of the roller and the trackway. The use of an inner flange of materially greater diameter than the trackway receiving groove permits a greater quantity of lubricant to be picked up by each roller. A relatively heavy lubricating oil or grease is employed, and with the construction described, the quantity of lubricant is sufficient for use over a long pe-

riod of time. The casing 36 forms a complete protection against injury to persons using the device, by the moving parts thereof. The casing fits snugly against the sides of the teeter board while the upper edges of the curved ends of the casing fit against the bottom of the board. The casing is relatively narrow in width, and is elongated longitudinally of the teeter board and transversely of the horizontal axis of oscillation, thus permitting the board to oscillate freely without causing the protecting casing to come into contact with any of the other parts of the apparatus.

It is to be understood that the form of the invention herewith shown and described is to be taken as a preferred example of the same and that various changes in the shape, size and arrangement of parts may be resorted to without departing from the spirit of the invention or the scope of the subjoined claims.

Having thus described my invention, I claim:

1. A device of the character described comprising a support provided with a series of undulations forming a trackway, a teeter board mounted above said trackway and supported to rotate about a vertical axis by said support, said board being adapted to partake of oscillation about a horizontal axis, and a pair of rollers carried by said board and adapted to engage said trackway, said support constituting a lubricant container into which portions of said rollers are adapted to dip.

2. A device of the character described comprising a trackway including a horizontal base portion and an upstanding circular side wall having undulations at its upper edge, a teeter board, means for supporting said board on said base portion for rotation about a vertical axis and oscillation about a horizontal axis, the low points of said side wall being arranged above said base portion whereby said trackway constitutes a lubricant container, and a pair of rollers carried by said teeter board and engaging said undulations, each of said rollers having a portion adapted to dip into said lubricant container.

3. A device of the character described comprising a trackway including a horizontal base portion and an upstanding circular side wall having undulations at its upper edge, a teeter board, means for supporting said board on said base portion for rotation about a vertical axis and oscillation about a horizontal axis, the low points of said side wall being arranged above said base portion whereby said trackway constitutes a lubricant container, and a pair of grooved roller mounted beneath said board for rotation and radial sliding movement with respect to their axes, each of said roll-

ers being provided on its inner side with an annular flange adapted to dip into said container.

4. A device of the character described comprising a trackway including a horizontal base portion and an upstanding circular side wall having undulations at its upper edge, a teeter board, means for supporting said board on said base portion for rotation about a vertical axis and oscillation about a horizontal axis, the low points of said side wall being arranged above said base portion whereby said trackway constitutes a lubricant container, a pair of shafts carried by said teeter board above diametrically opposite portions of said undulations, and a grooved roller rotatably and slidably mounted on each of said shafts and engaging said undulations, each of said rollers being provided at its inner side with an annular flange of materially greater diameter than the grooved portion thereof and adapted to dip into said container.

5. A device of the character described comprising a trackway provided with a series of undulations, a teeter board mounted above said trackway to rotate about a vertical axis and to oscillate about a horizontal axis, a pair of rollers carried by said board and adapted to engage said undulations, and a protecting casing carried by said board and extending downwardly to surround said trackway and said rollers, said casing being substantially equal in width to said board and longitudinally elongated with respect thereto, whereby oscillation of said board will not be prevented by the sides of said casing.

In testimony whereof I affix my signature.

EWING HORACE TAYLOR.
